(57) **CLAIM**

The ornamental design for a standing form supporting frame for supporting cup-like objects, as shown and described.

DESCRIPTION

FIG. 1 is a perspective view of a standing form supporting frame for supporting cup-like objects showing my new design
FIG. 2 is a front elevational view thereof
FIG. 3 is a rear elevational view thereof
FIG. 4 is a left side view thereof
FIG. 5 is a right side view thereof
FIG. 6 is a top plan view thereof
FIG. 7 is a bottom plan view thereof; and,
FIG. 8 is a perspective view showing the application of the present invention, where those indicated by dashed lines are not claimed.
